ELECTRIC FOLLOW-UP SWITCH

George Olah, London, England, assignor to Precision Developments Company Limited, London, England, a corporation of Great Britain

Application July 14, 1943, Serial No. 494,736
In Great Britain April 29, 1942

4 Claims. (Cl. 200—52)

This invention relates to the arrangement of contact carrying members in switch gear and more especially to types of switch gear in which the amount of displacement of the movable member is not determined solely by the requirements of the switching operation but bears a definite relationship to an interconnected displacement in the mechanism of which the switching member forms part.

Switching devices of this kind are used extensively in various types of electric control apparatus particularly as limit switches, selector switches and follow-up switches.

More particularly this invention concerns switching devices of the type referred to above in which a plurality of contacts is to be controlled by one movement of the movable member.

In switching devices of the type referred to it is most convenient and natural to use contact surfaces at the same time as limiting or transmitting members for mechanical movement. In fact any arrangement in which these two functions are separated would require extreme care in manufacture and adjustment to obtain any contact at all and even under most favourable conditions the contact pressure and therefore also the contact resistance of an individual contact would be uncertain.

In many switching devices of the general type it is customary to arrange cooperating contacts to slide on each other while performing the switching operation. In such cases the switching of a plurality of circuits presents no difficulties. The contact pressure bears no relation to the switching movement.

In another type of construction the contact carrying members are all mounted resiliently on the main movable or stationary member. In this case there is also no particular difficulty associated with the number of contacts to be operated simultaneously. The contact pressure is determined by the amount of displacement in the switching motion and distributed according to the resilience of the mounting of the individual members.

Both of the last mentioned switch designs are not easily applicable to devices to which this invention applies, where contacts must be made and broken fully and solely upon the occurrence of a definite and limited displacement of the movable member.

It is the purpose of the present invention to provide simple and effective means for switching of a plurality of contacts by a strictly controlled and limited movement, producing equal contact

pressure on all contacts and to obtain this result without requiring undue accuracy in manufacture and adjustment.

According to the present invention in a switching device which performs the closure and interruption of at least two pairs of cooperating contacts fully and solely controlled by a definite and limited relative displacement between a movable and a stationary member and in which the contact surfaces coincide with limiting or transmitting surfaces for the said relative displacement an additional member is provided which is freely floating between the two aforesaid members and which carries at least one each of the several pairs of contacts controlled by the switching device.

In order that the invention may be better understood and applied it will now be described in detail in its embodiment in several types of follow up switches with reference to the accompanying drawings, in which Fig. 1 shows diagrammatically an arrangement in which an electric servo motor is controlled by a follow up switch to achieve positional correspondence between an input handle and an output shaft.

Figs. 2 and 3 show the detail arrangement of the follow up switch indicated diagrammatically in Fig. 1 and show also the electrical circuit in diagrammatic form, Fig. 3 being a transverse section on the line S—S of Fig. 2.

Figs. 4 and 5 show the application of the invention to a different type of follow up switch which can be employed in the arrangement shown in Fig. 1, Fig. 5 being a section on the line A—A of Fig. 4.

Referring to Fig. 1, 1 indicates an electric servo motor driving a movable object 2 (such as a ship's rudder) and 3 is a follow up switch controlling the servo motor to achieve positional correspondence between an input handle 4 on a shaft 6 and an output shaft 5.

As indicated in more detail in Figs. 2 and 3, the input member A consisting of a hollow cylinder integral with the input shaft 6 and carrying a radially extending insulated contact member AX in the form of a bar with two contact surfaces A1 and A2 on opposite sides. This contact member is connected by a flexible wire A3X to the slip ring A3 which cooperates with a brush A4 connected to a collector brush A5 of the servo motor 1 shown as a D. C. motor.

The output or follow up member B consists of a hollow cylinder sleeving the member A and integral with the output shaft 5. The follow-up member B carries a radially extending insulated

contact member BX in the form of a bar having two opposite contact surfaces B1 and B2 and connected by a flexible wire B3X to a slip ring B3 cooperating with a brush B4 which is connected to the opposite commutator brush B5 of the motor 1.

Between the two members A and B there is interposed a floating member CD which carries four insulated contact members with contact surfaces C1, D2 between which bar AX projects and C2, D1 between which the bar BX projects.

The contacts C1, C2 are both connected by flexible wires C1X and C2X respectively to slip ring C3 cooperating with brush C4 while the contacts D1, D2 are connected by flexible wires D1X and D2X to slip ring D3 cooperating with brush D4. The brushes C4, D4 receive the two poles of an electric D. C. supply.

The contact surfaces are so adjusted that when the floating member CD is in its central position there is an air gap between all of the cooperating contact surfaces sufficient to provide insulation against the voltage of the circuit.

The operation of the switch is as follows:

When the controlling or input member A moves clockwise in Fig. 2, the contact surface A1 on the contact member AX first makes contact with contact C1 on the floating member CD and then by driving the floating member CD presses the contact surface D1 on the floating member against the contact surface B1 on the bar BX. Equal pressure is thus transmitted through both pairs of contacts. A circuit is now established from the positive pole of the electric D. C. supply through brush C4, slip ring C3, flexible wire C1X, contact surface C1, contact member AX, flexible wire A3X, slip ring A3, brush A4, brush B4, slip ring B3, flexible wire B3X, contact member BX, contact surface D1, flexible wire D1X, slip ring D3 and brush D4 to the negative pole of the electric D. C. supply of the servo motor 1. The motor 1 now starts rotating, its polarity being assumed to be such that it drives the output member B and shaft 5 in the same direction in which the input shaft has been moved. As soon as the motor overtakes the input drive the contacts separate, the circuit is interrupted and the motor decelerates, whereupon, provided the input shaft 6 continues to rotate a new contact is made and so on.

Following the movement of the controlling member A in the opposite direction it will be observed that the polarity of the collector brushes is reversed whereupon the servo motor 1 starts its movement in the opposite sense.

In each case the deceleration of the servo motor upon interruption of its circuit may not be quick enough and the output member B of the switch may continue to overtake the input member A until the reverse circuit is established which would generate a strong braking torque until the deceleration is sufficient for the input member to overtake the output member again and re-establish the driving torque.

In the embodiment shown in Figs. 4 and 5 which can also be employed in the arrangement shown in Fig. 1 the actual current carrying elements of the device are stationary, and all slip rings and brushes are avoided.

The reaction torque on the planetary member P in an epicyclic gear train is used to effect the switching operation of a change over switch. This reaction torque is dependent on the direction of the relative motion between the input and

output gear and can therefore be used to actuate a reversing switch in a follow up mechanism.

In this embodiment 5 indicates as before the input shaft and 6 the output shaft coupled through an epicyclic train to shaft 5. The end of the input shaft 6 has an enlarged portion E formed integrally therewith. The enlarged portion E has a central recess E1 forming a bearing for an end 51 of the output shaft 5, and a flange 10 portion terminating in a ring gear E2. A sun gear 52 is formed integrally with the output shaft 5 and meshes with planetary gears F and F1 mounted for rotation on studs G and G1 firmly anchored in a planetary member P mounted for 15 rotative movement about the output shaft 5. The planetary gears F and F1 mesh with the ring gear E2. Planetary member P carries an insulated contact AX' having contact surfaces A1' and A2', while the floating member CD' is provided with four contacts C1', C2' and D1', D2' as in the previous embodiment.

From an examination of Figs. 4 and 5 it will be evident that when input shaft 6 is rotated in the clockwise direction with the output shaft 5 stationary and having a substantial resistance to motion, the planet member P will be rocked in the same direction and contact pairs C1', A1' and D1', B1' will make contact, thereby establishing a circuit from the positive pole of the electric D. C. supply through contact member C1', contact face A1', contact AX' collector brushes A5' and B5' of servo motor 1, contact BX', contact face B1' and contact member D1' to the negative pole of the electric D. C. supply, to start rotation of 25 the servo motor until the motor causes the output shaft 5 to overtake the input shaft 6, when the planetary member P will be rocked back and interrupt the motor circuit. It will be seen that apart from the mechanical arrangement of the 30 follow up switch, the circuit connections are identical with those of Fig. 2.

Inverse rotation of the input shaft will operate contact pairs C2', A2' and D2', B2' and complete the motor circuit with reversed polarity.

The epicyclic gear mechanism used for operating the follow up switch can be of the simple or compound type and since only a very small movement is required the pivot centre of the planetary member P may not coincide with the sun centre at all.

It will be understood that the invention is not limited to the devices described in the accompanying drawings but can be applied to contact members of any shape or form, to switches for any purpose and type of circuit. The actuating mechanism can be made to suit any requirement of operation. The movement of the floating member can be rotative or rectilinear and any number of circuits can be controlled by additional floating members.

In my Patent No. 2,387,174 I have described and claimed a braking mechanism for an electric motor comprising a brake member connected to the motor shaft for rotation thereby, an electro-magnetically operated friction brake positioned to apply a braking action on the brake member, electrical connections for the electric motor and the electro-magnetically operated brake including a coil connected across the electric supply terminals for the electric motor for generating the magnetic force for applying the brake, and at least one compensating coil counteracting the magnetomotive forces of the first-mentioned coil whenever the electric motor is in circuit, whereby a braking action is exerted upon the brake mem-

ber when the electric motor is disconnected from the supply of electric current, but said first-mentioned coil still is connected thereto, and no braking action is exerted on the brake member either when the motor is in circuit or the supply of electric current to said first-mentioned coil is interrupted, and in which the supply of electric current to the motor includes a first member, a second member, a member floating between said first and second members, and electric contact surfaces carried by said first and second members and the floating member for completing an electric circuit to the motor when either the first or second member is moved a predetermined distance relative to the other. I make no claim herein to the arrangement claimed in my said patent. Subject to this disclaimer, the invention claimed herein is set forth in the appended claims.

I claim:

1. An electrical switching device comprising a first movable contact-carrying member, a second movable contact-carrying member, said members being mounted for movement relative to one another, the first contact-carrying member having a contact surface which also serves as a movement limiting and a motion transmitting surface, said second contact-carrying member having a contact surface which also serves as a movement limiting and a motion transmitting surface, at least one floating member located in the path of movement of the contact surfaces of said first and second contact-carrying members, said floating member having contacts adapted to be engaged by the contacts of said first and second contact-carrying member, the respective parts being so constructed and arranged that when one of the contact-carrying members is moved in one direction relative to the other contact-carrying member, the contact surface of the floating member will be in engagement with the contact surfaces of said first and second contact-carrying members and the floating member will be locked between said contact-carrying members and afford means for imparting movement from one contact-carrying member to another contact-carrying member.

2. An electrical switching device comprising a first movable contact-carrying member, a second

movable contact-carrying member, said members being mounted for movement in opposite directions relative to one another, each of said contact-carrying members having contact surfaces on opposite sides which also serve as movement-limiting and motion-transmitting surfaces, and at least one floating member having portions located in the path of movement of the contact surfaces of said first and second contact-carrying members, said floating member having contacts on said portions adapted to be engaged by the contacts on the first and second contact-carrying members, the respective parts being so constructed and arranged that after one of the contact-carrying members has moved a limited amount in either direction relative to the other contact-carrying member a contact surface of said contact-carrying member will engage the cooperating contact surface of the floating member and thereafter move the floating member until a contact thereof engages the cooperating contact of the other contact-carrying member, after which the floating member is locked between the two contact-carrying members and serves as a motion-imparting means between said contact-carrying members, the floating member floating freely between the contact-carrying members when contact surfaces carried thereby are not engaged by the contact surfaces of either contact-carrying member.

3. An electrical switching device as set forth in claim 2 in which the first-mentioned contact-carrying member closes two alternate pairs of contacts at each end of its free movement relative to the floating member and at least one pair of said alternate pairs of contacts when in an intermediate position relative to the floating member, and in which connections extend from the respective contacts of the contact-carrying members and the floating member to commutate two poles of an electrical supply with two terminals of an electrical device.

4. An electrical switching device as set forth in claim 2 in which the contact carrying members and the floating member are mounted for rotary movement in opposite directions about a common axis.

GEORGE OLAH.
